EQUALIZER SYSTEM

Allen Wallace, Moorestown, N. J.

Application June 29, 1933, Serial No. 678,243

8 Claims. (Cl. 105—82)

This invention relates generally to locomotives and more particularly to an improved spring and equalizing system especially adapted for electric locomotives.

It is desirable in locomotives, particularly of the high speed type, to have the spring system sufficiently flexible consistent with stability so as to permit not only smooth riding of the locomotive but also to minimize excessive wear on the tracks, switches and roadbed. Due to the complicated character of present-day locomotives, it is necessary that any improved equalizing and spring system should be readily, economically and efficiently adapted to the generally accepted designs of locomotives without extensive alterations thereto or impairment of operation thereof.

It is one object of my invention to accomplish the foregoing results in an improved equalizing and spring system particularly for the guiding trucks of a locomotive. Another object is to provide an improved combination in an equalizing system having an improved combined spring housing and center plate for trucks of the pivoted types.

A still further object is to provide an improved combination involving the main equalizing system for the locomotive driving wheels and an improved equalizing system for the trucks, these systems being interconnected in an improved manner.

Another object is to provide an improved arrangement whereby the main spring system over each of the driving boxes at each side of the locomotive may be brought into effective cooperation with a truck spring system which is disposed centrally of the truck and supported by an improved combined spring housing and center plate.

Other objects and advantages will be more apparent to those skilled in the art from the following description of the accompanying drawings in which:

Fig. 1 is a fragmentary elevational view of one end of the locomotive with parts broken away to show details of construction with my improved equalizer system;

Fig. 2 is a plan view of a portion of my equalizer system, various parts of the locomotive being omitted for sake of clarity;

Fig. 3 is a partial vertical section taken on the line 3—3 of Fig. 1;

Fig. 4 is a vertical section taken on the line 4—4 of Fig. 1;

Fig. 5 is a partial vertical section taken on the line 5—5 of Fig. 1;

Fig. 6 is a partial vertical section on the line 6—6 of Fig. 1.

In the illustrated embodiment of the invention which is shown herein merely for the purpose of disclosing one specific form among possible others that the invention might take, I have incorporated my improved equalizing system in any suitable type of locomotive construction preferably of the electric type having, for example, a main frame 1 and driving wheels 2 whose axles are suitably journalled in journal boxes 3. These boxes as is usual are vertically slidably guided in pedestal guides 4. Main springs 5 are pivotally supported as at 6 on top of journal boxes 3, the springs preferably being in pairs one on each side of the side sills of main frame 1 as shown in Fig. 5. The ends of springs 5 are connected to any suitable or usual type of equalizing system including an equalizing beam 7. One end of this beam is link connected to one end of springs 5 while the other end of beam 7 is connected in the same manner to the springs over the next driver wheels. Hence it is sufficient to disclose only this fragmentary portion of the main equalizing and spring system as it is duplicated for as many driver wheels as there may be. The connection of beam 7 to spring 5 is, preferably, by a pair of vertical links 8 and common cross link 9 to which one end of a link 10 is pivotally connected while its other end is pivotally connected as at 11 to equalizer beam 7.

A usual pivoted truck 12 serving either as a leading or trailing truck is arranged in a novel manner to incorporate an equalizing and spring system which in turn is associated with the main equalizing system for the drivers. To accomplish this I have provided an improved combined center plate and spring housing or support generally indicated at 14. This construction as shown more particularly in Fig. 3 includes an annular center pin recess 15 formed by a cylindrical flange carried by a truck bolster 16. This bolster can swing laterally in the usual manner relatively to its truck due to being supported through heart links 17 and 17' whose lower ends are pivotally connected as at 18 and 19 to the bolster while their upper heart shaped ends are pivotally connected in the usual manner at 20 and 21 to the crosstie 22 of the truck frame.

Journalled in recess 15 is a cylindrical pin portion 23 projecting downwardly from the combined member 14. The upper portion 24 of this combined member is preferably rectangular in

plan view such as shown at the right end of Fig. 2, and this upper end serves as a guide post having 5
slidable engagement with a suitable vertical guiding wall 25 disposed preferably centrally between
the side sills of the locomotive frame 1 but connected thereto in any desired manner by a cross-tie 26 or the like. As the details of the truck 12
do not otherwise enter into my improved combination, it will suffice to state that other usual
10 structural features of the trucks are employed
such as springs, equalizers, etc.

A longitudinal leaf spring assembly, preferably
a pair such as 27 and 27' disposed in relatively
close preferably substantially parallel relation,
15 extends through suitable openings 28 and 29 of
the center pin member 14 and specifically through
that portion thereof forming the guide post.
These springs are suitably pivotally supported as
at 30 on the beam portions 31 and 32 of the center
20 pin and spring housing 14. The front ends of
springs 27 and 27' pivotally support the main
frame 1 through a suitable spring seat and spring
links generally indicated at 33 and 34, Figs. 1 and
2, while the rear ends of said springs are provided
25 with links 35 and 36 respectively pivotally connected
to the front end of equalizer beams 37 and
37'. These beams as shown in Fig. 1 are pivotally
connected at 39 substantially midway of their
length to a crosstie 38 of the main frame. From
30 the foregoing it is seen that the spring and equalizer
systems are duplicates, one disposed on each
side of the center line of the main frame. Hence
in the description hereafter it will be only necessary
35 to refer to the system on one side as the other side will be the same. The rear end of beam
37 is pivotally supported by the front end of main
spring 5, this pivotal connection being effected
by a linkage arrangement such as shown in Fig. 5,
and hence corresponding parts are given the same
40 reference numbers. It will be further noted that
the equalizer beam 37 and its complementary
beam 37' extend inwardly preferably on substantially
straight diagonal lines from the main
springs 5 to the central truck spring assembly
45 such as springs 27 and 27' which are disposed
relatively close together to cooperate with the
combined center pin and spring housing.

The foregoing effects not only an extraordinary
degree of compactness but also insures maximum
50 flexibility and smoother riding of the leading or
trailing trucks together with a stable system
due to its positive vertically slidable connection
with the main frame at the central part thereof.
Also the main equalizing system on each side of
55 the frame can cooperate independently with their
respective truck springs 27 or 27' without causing
undue stresses or of disturbing in any way the
operative relation between the center pin 23
and the vertical guiding relation between the
60 spring housing 24 and frame recess 25. Certain
of these results are due to the rectangular forma-
tion in plan view of post 24, thus preventing ro-
tation of the spring housing with respect to the
main frame while at the same time permitting
65 substantial relative vertical movement to take
place between the spring housing and the main
frame to insure complete functioning of the equal-
izer system during relative movement between
the truck and main frame. In this manner the
70 front ends of springs 27 and 27' can have a fixed
pivotal connection such as 33 and 34 to the main
frame without in any way interfering with the
complete pivotal movement of the truck on center
pin 23. Hence it is seen that I have provided
75 a relatively simple, compact and yet economical

and durable equalizer system for leading and
trailing trucks particularly of an electric locomotive
in combination with the main equalizing and
spring system.

It will of course be understood by those skilled
in the art that various changes may be made
in details of construction and the parts rear-
ranged without departing from the spirit of the
invention as set forth in the appended claims.

I claim:

1. A railway vehicle comprising, in combina-
tion, a frame, wheels and axles therefor, a spring
and equalizing system for supporting said frame
by said wheels, a truck, a member having a guide
post supported in relatively slidable relation to
15 the frame and a center pin pivotally supported on
said truck, said post having an opening therein,
a longitudinal spring system extending through
said opening, means for connecting one end of
said latter spring system to said frame, and an
equalizer beam connecting the other end of said
latter spring to the spring and equalizing system
for said wheels.

2. A railway vehicle comprising, in combina-
tion, a main frame, wheels, a main spring and
equalizing system through which said frame is
supported by said wheels, a truck, means for
pivotally supporting said frame on said truck
and having vertical slidable surface connections
with said frame and an opening located between
25 planes containing said slidable surfaces, and a
spring and equalizer system extending through
said opening and operatively supported by said
pivotally supported means and interconnected with
said main equalizing system.

3. A railway vehicle comprising, in combina-
tion, a main frame, wheels, a main spring and
equalizing system through which said frame is
supported by said wheels, a truck, means for
pivotally supporting said frame on said truck
40 and having vertical slidable connection with sides
of said frame and a horizontal opening located
between said sides, and a spring extending
through said opening of the pivotal means and an
equalizer system operatively supported by said
45 pivotal means and interconnected with said equal-
izing system.

4. A railway vehicle comprising, in combina-
tion, a frame, wheels therefor, a main spring and
equalizing system through which said frame is
50 supported on said wheels, a truck, a combined
spring housing and center pin journalled on said
truck and having non-rotatable but relatively
vertical slidable movement with opposed walls of
said frame, a spring extending through and sup-
55 ported by said combined member longitudinally
of said frame and located between said opposed
walls, means for connecting one end of said latter
spring and said frame, and an equalizer beam
connecting the other end of said latter spring to
60 said main spring and equalizer system.

5. A locomotive comprising, in combination, a
frame, driving wheels, a main spring and equal-
izing system for supporting said frame on said
wheels, a truck, a combined spring support and
65 center pin member journalled on said truck, said
combined member having slidable but non-rotat-
able engagement with the walls of an opening
in said frame, a spring extending through and
carried by said combined member and extending
70 longitudinally of and within said frame, means
for connecting one end of said latter spring to
said frame, and an equalizer beam connecting
the other end of said latter spring to said main
spring and equalizing system.

6. A locomotive comprising, in combination, a frame, driving wheels, a main spring and equalizing system for supporting said frame on said wheels, a truck, a combined spring support and center pin member journalled on said truck, said combined member in plan view having its greatest dimension transversely of the frame and an opening extending transversely of said greatest dimension, said frame having an opening similarly shaped to said member to vertically slidably receive the same, a spring extending through said transverse opening and carried by said combined member and extending longitudinally of said frame and located between opposed portions of the frame, means for connecting one end of said latter spring to said frame, and an equalizing beam connecting the other end of said latter spring to said main spring and equalizing system. 5
7. A locomotive comprising, in combination, a main frame, driving wheels, a main spring and 10
- 15
- 20
- equalizing system for supporting said frame on said wheels, a truck, a combined spring housing and center pin member journalled on said truck and having relatively vertical slidable engagement with said frame, a pair of substantially parallel springs each extending through and carried by said member and extending longitudinally of and within said frame and connected thereto, and equalizer beams independently connecting the other end of said latter springs with 10 said main spring and equalizing system. 15
8. The combination set forth in claim 7 further characterized in that said substantially parallel springs are disposed centrally of said frame and said equalizer beams extend diagonally outward from said springs to the sides of said frame for connection to the main spring and equalizing system. 20
